US00D986988S

(12) **United States Design Patent** (10) **Patent No.:** **US D986,988 S**
(45) **Date of Patent:** **** May 23, 2023**

(54) **SPORTS EQUIPMENT LIMITER**

(71) Applicant: **Qiongfang Mao**, Zhejiang (CN)

(72) Inventor: **Qiongfang Mao**, Zhejiang (CN)

(**) Term: **15 Years**

(21) Appl. No.: **29/884,358**

(22) Filed: **Feb. 10, 2023**

(51) **LOC (14) Cl.** **21-02**

(52) **U.S. Cl.**

USPC **D21/673**

(57) **CLAIM**

The ornamental design for a sports equipment limiter, as
shown and described.

DESCRIPTION

FIG. 1 is a front perspective view of a sports equipment limiter, showing my new design;

FIG. 2 is a rear perspective view thereof;

FIG. 3 is a right perspective view thereof;

FIG. 4 is a front elevational view thereof, the rear elevational
view being a mirror image of FIG. 4;

FIG. 5 is a left side view thereof;

FIG. 6 is a right side view thereof;

FIG. 7 is a top plan view thereof;

FIG. 8 is a bottom plan view thereof; and,

FIG. 9 is a rear perspective view of the sports equipment
limiter in a used state.

The broken lines in the figures are for the purposes of
illustrating portions of the sports equipment limiter, which
form no part of the claimed design.

1 Claim, 5 Drawing Sheets
